C. P. DAIBER.
ALVEOLAR TREATMENT APPARATUS.
APPLICATION FILED DEC. 27, 1915.

1,202,971.

Patented Oct. 31, 1916.

UNITED STATES PATENT OFFICE.

CHARLES P. DAIBER, OF LOS ANGELES, CALIFORNIA.

ALVEOLAR-TREATMENT APPARATUS.

1,202,971.

Specification of Letters Patent. Patented Oct. 31, 1916.

Application filed December 27, 1915. Serial No. 68,721.

To all whom it may concern:

Be it known that I, CHARLES P. DAIBER, a citizen of the United States, residing in Los Angeles, in the county of Los Angeles and State of California, have invented a new and useful Improvement in Alveolar-Treatment Apparatus, of which the following is a specification.

The invention relates to dental suction apparatus and the principal object is to provide a simple and economically operated dental massage device for individual use.

It is also an object to provide a vacuum producing device in connection with an applicator of suitable form that may be operated by a sufferer from gum disease, the power required being supplied by the common water supply.

It is a further object to provide a simple controlling means in conjunction with the applicator and vacuum member by which the suction may be varied, intermittent or altered to suit individual requirements.

It is a still further object to provide a receptacle in connection with the controlling device which is of a transparent material so that the results of the suction and treatment may be visible and no secretions or exudates removed in the treatment will be carried into the other tubes and interfere with the efficiency of the apparatus.

In the drawings accompanying this specification Figure 1 is a general view with the parts in section and clearly showing the application of the invention. Fig. 2 is a transverse section on the line 2—2 of Fig. 1 and Fig. 3 is a section on the line 3—3 of Fig. 1, both sections being viewed in the direction of the arrows.

More specifically in the drawings numerals are used to designate the component parts, the numeral 5 designating the gum applicator of well known construction, provided with the engaging lips 6—6 adapted to extend on either side of the gum in close approximation to the margins of the teeth, the lips widening to a base that preferably is provided with a channel that communicates with a nipple 7 to which the flexible tube 8 is secured. This tube 8 is of such length as to readily reach from the receptacle 9 when held in the patient's hand with the applicator applied to the patient's gums, this receptacle being formed of a transparent

body 10 of convenient form to be held in 55 the hand and tightly closed by the apertured member 11.

The member 11 is formed of metal and is provided with the nipple 12 engaged by the tube 8, this nipple having a passage there-through and extending downwardly in the body of the closure and preferably extended into the container below the level of the other channel by the small tube 14. The other channel communicates with another 60 65 and oppositely disposed nipple 15 which is adapted to afford communication with a flexible tube 16. Intermediate these two channels and communicating directly to the outside is another channel or bore that is 70 tapered at its inner portion to form a seat for the valve 17, this valve being provided with a valve stem that extends through the bore and is surrounded by a coiled spring 18. This spring 18 bears against the outer surface of the closure and against the lower portion of the head 19 secured to the valve 75 stem in any well known manner, so that the spring holds the valve normally closed against the amount of vacuum formed by 80 the vacuum producing member, a bore 20 affording communication with the bore for the valve stem to relieve the vacuum. This vacuum or partial vacuum producer consists of a body 21 and a neck provided with a 85 bore that affords communication with the nipple 22 to which the other end of the long tube 16 is secured, this bore communicating with the axially disposed bore 23, being preferably for the lower portion of its length 90 parallel with bore 23 and joining the latter below its communication with the concentric and also straight bore 24 that affords communication with the bowl 25, this bore 24 being of less diameter and in line with 95 the bore 23, these relations being a condition precedent to the efficient operation of the device.

The bowl 25 is provided with an apertured closure 26, the aperture therein being 100 of such size as to fit over the common water bib, cock or faucet and allow the outlet of the latter to be securely and watertightly gripped by the flexible gripper or gasket 27, which is held in place by the closure and 105 is preferably of the somewhat inverted cone shape, to allow the water to fill the large bowl provided and exert a steady and eddy

free pressure of the water from the source to which the faucet is an outlet. This member is preferably of metal and to cover the plugs (not shown) that are required in the machining to produce the form of the bores for the air from the nipple 22 and to lighten the structure as well as to extend the length of the water channel, the tube 28 is fitted over the neck and extends 5 some distance below the end of the bore 23, and serves as a support for the wire screen 10 29 or a perforated plate as desired, placed slightly above the outlet so as to break the force of the water and prevent splashing as 15 it passes away.

The operation will be readily understood, the proper size applicator having been determined, the vacuum member is placed over the bib and the water turned on, and the 20 requisite suction is created at the applicator, namely to clamp the lips 6—6 firmly to the gums, and withdraw any secretion adjacent thereto, and this pressure may be intermittently produced to produce massage by an operator or the 25 patient, on whom the treatment is made, this device being particularly adapted for the treatment and cure of pyorrhea, the secretions being collected in the receptacle 10 and the suction relieved or lessened by pressure on the valve 17 by the thumb of the 30 hand holding the receptacle.

What I claim is:—

1. A dental suction and massaging apparatus, comprising an alveolar applicator, a 35 tube connected therewith, and also connecting with an inlet into a valved secretion retainer, a secretion retainer provided with adjacent inlet and outlet passages, means to control said valved secretion retainer and a

vacuum producing member secured to the 40 outlet of said receptacle.

2. A dental apparatus adapted to treat the gums, comprising a gum applicator provided with a passaged nipple, a tube attached to said nipple and one opening in a 45 valve controlled receptacle, a valve controlled receptacle adapted to retain and show secretions and provided with a plurality of openings, and a vacuum producing member connected to the other of said openings in 50 said receptacle.

3. A dental gum treating apparatus comprising a gum applicator, a tube connected therewith, a vacuum controlling member attached to the other end of said tube, a second tube connected to said controlling member and to a vacuum producing member, and a vacuum producing member provided with a chambered body having a bowl and a bore of small size, said bore entering a larger 60 bore concentric thereto to carry water from said bowl, together with an air carrying bore entering said larger bore and affording communication with said second tube, whereby 65 suction is produced in said applicator.

4. An alveolar treating device comprising a dental suction applicator, a tube connected therewith, a valved suction controlling member connected to the other end of said tube, said member having a channel extending 70 into a dependent secretion holding member, a dependent secretion holding member secured to said valved suction controlling member, a second tube connected to said controlling member, and a suction producing member secured to the other end of said 75 second tube.

CHARLES P. DAIBER.
